L. B. SHARPNACK.

ROTARY VENTILATOR.

APPLICATION FILED MAY 26, 1919.

1,314,432.

Patented Aug. 26, 1919.

UNITED STATES PATENT OFFICE.

LORD B. SHARPNACK, OF DETROIT, MICHIGAN.

ROTARY VENTILATOR.

1,314,432.

Specification of Letters Patent. Patented Aug. 26, 1919.

Application filed May 26, 1919. Serial No. 299,847.

To all whom it may concern:

Be it known that I, LORD B. SHARPNACK, a citizen of the United States of America, residing at Detroit, in the county of Wayne 5 and State of Michigan, have invented certain new and useful Improvements in Rotary Ventilators, of which the following is a specification, reference being had therein to the accompanying drawings.

10 This invention relates to ventilators, and has special reference to that type located in the open and automatically adjusted by air currents or transient wind to produce or increase, by aspiration, drafts within the ventilator, so that a circulation of air may be maintained in a building or compartment thereof. Such ventilators are also employed in connection with the discharge of smoke, 15 gases and vapors from buildings, and also from analogous structures.

20 The primary object of my invention is to provide a ventilator of the above type with a novel cowl or rotary casing in a portion of which a partial vacuum or suction may be produced to expeditiously remove air and other matter from the outlet connection of the ventilator.

Another object of my invention is to provide a ventilator wherein the movable parts 30 are perfectly balanced and supported for operation with a minimum friction and possibility of displacement.

A further object of my invention is to provide a ventilator wherein the parts are 35 constructed with a view of reducing the cost of manufacture and at the same time retain those features by which durability, simplicity of construction and ease of assembling are secured. With such ends in view, my 40 invention resides in the novel construction to be hereinafter considered and then claimed.

Reference will now be had to the drawing, wherein—

45 Figure 1 is a vertical sectional view of the ventilator, partly in elevation;

Fig. 2 is a plan of the same, partly broken away and partly in section;

Fig. 3 is an enlarged detail sectional view 50 of a cowl bearing, and

Fig. 4 is a vertical sectional view taken on the line IV—IV of Fig. 2.

In the drawing, the reference numeral 1 denotes a vertically disposed cylindrical outlet connection and suitably secured to the 55 upper end thereof is a plurality of uprights

2 having the upper ends thereof bent inwardly and disposed at an angle, as at 3, so that a conical shaped hood 4 may be mounted on the upper ends of said uprights. The 60 hood 4 is maintained in a spaced relation to the upper end of the outlet connection 1 and is of a greater diameter than said outlet connection so as to prevent rain from entering the outlet connection or falling on other elements of the ventilator.

The plurality of uprights 2 support superimposed circular deflectors 5 and cooperate with the hood 4 in deflecting air outwardly at all sides of the connection 1, between the 70 upper end of said connection and said hood.

The apex of the hood 4 is provided with a cap 6 having a socket or fulcrum bearing 7 for the center piece 8 of a spider 9. The center piece 8 has a central pin or boss 10 75 extending into the socket 7 and a depending wall or apron 11 of said center piece prevents accidental lateral displacement of the spider relative to the hood. The spider 9 is preferably in the form of a plurality of 80 angularly disposed arms preferably disposed in parallelism with the hood 4 and on the lower ends of said arms is a cowl or rotary casing 12 which surrounds the upper end of the outlet connection 1 in spaced relation thereto. To maintain this relation the inner wall of the cowl adjacent the lower end thereof, has a plurality of inwardly projecting bearings 13 for anti-frictional wheels or rollers 14 that travel in a channel track or 90 member 15, carried by the outer wall of the connection 1. It is through the medium of these anti-frictional wheels and the fulcrum of the spider that the cowl may freely revolve relative to the outlet connection 1 and 95 its hood 4.

Diametrically opposed walls of the cowl 12 are provided with inlet and outlet openings 16 and 17, the former admitting air to the cowl and the latter permitting air 100 to exhaust therefrom. Both of these openings have side wings 18 and to maintain the openings in the wind or in alinement with a draft of the spider 9 is provided with a vane 19, which may be secured to one of the 105 spider arms and connected to the cowl by side braces 20.

Projecting inwardly from the walls of the cowl 12 are brackets 21 supporting a somewhat circular or curved shell 22 which 110 has its lower end surrounding the outlet connection 1 and its upper end extending into

the hood 4. The shell 22 coöperates with the cowl in providing a conduit 23 communicating with the air intake opening 16 so that air entering the cowl will be deflected at the shell 22 into the conduit 23, said conduit having its ends opening in proximity to the exhaust opening 17 of the cowl. The inrush of air in the opening 16 and through the conduit 23 will produce a partial vacuum or 10 suction beneath the hood 4 and at the upper end of the outlet connection 1, so that a draft will be produced in the outlet connection 1 and any other conduits or connections therewith. The ventilator will therefore positively draw air from the outlet connection 1, especially when there is an air current or transient wind in which the ventilator is maintained by the vane 19.

To further deflect the air or gases emitted 25 by the outlet connection 1 and prevent an eddy in the top of the hood 4, said hood has a central inverted conical shaped deflector 24 and air and gases impinging against this deflector are directed outwardly from beneath said hood. The draft produced in the branches of the conduit 23 is sufficient to quickly exhaust air from the upper end of 30 the outlet connection 1, and the air will be deflected downwardly from under the cowl by the deflector 5 or outwardly through the exhaust opening 17 thereof.

It is thought that the operation and utility of the ventilator will be apparent without further description, and while in the drawing there is illustrated the preferred embodiment of my invention, it is to be understood that the structural elements are susceptible to such variations and modifications as fall within the scope of the appended 40 claims.

What I claim is:—

1. A ventilator comprising an outlet connection, a hood above said connection, a cowl surrounding said hood and supported 45 thereby, and a shell in said cowl adapted to produce a draft beneath said hood and at the upper end of said outlet connection.

2. A ventilator as characterized in claim 1, and wherein a spider having a central bearing on said hood supports said cowl.

3. A ventilator as characterized in claim 1, and wherein a series of annular deflectors

are supported between said outlet connection and said hood.

4. A ventilator comprising an outlet connection, a hood above said outlet connection, a spider having a central fulcrum bearing on said hood, a cowl carried by said spider about said hood and adapted to produce a partial vacuum at said outlet connection. 55 60

5. A ventilator as characterized in claim 4, and wherein a track and wheels brace the lower end of the cowl relative to the outlet connection.

6. A ventilator as characterized in claim 4, and wherein deflectors are arranged between the outlet connection and the hood.

7. A ventilator comprising a rotatable cowl having air intake and exhaust openings, and a shell supported in said cowl providing a conduit open at its middle portion to the air intake opening of said cowl and having its ends open at the exhaust opening of said cowl and adapted to produce a suction centrally of said shell. 70 75

8. A ventilator as characterized in claim 7, and wherein a central bearing supports the upper end of the cowl, and wheels brace the lower end thereof.

9. A ventilator comprising an outlet connection, uprights carried thereby, a hood supported by said uprights, a fulcrum bearing on said hood, a spider supported from said bearing, a cowl carried by said spider surrounding the upper end of said outlet connection, said cowl having air intake and exhaust openings, a shell supported in said cowl and coöperating therewith in providing a conduit open at its middle portion at the air intake opening of said cowl and having its ends open at the exhaust opening of said cowl, and means bracing the lower end of said cowl relative to said outlet connection. 80 85 90 95

10. A ventilator as characterized in claim 9, and wherein a series of deflectors are supported by said uprights between said outlet connection and said hood.

In testimony whereof I affix my signature in the presence of two witnesses.

LORD B. SHARPNACK.
